ATTORNEY

UNITED STATES PATENT OFFICE.

CHARLES EDGE, OF NEWARK, NEW JERSEY.

TOOL FOR CUTTING KNITTED WIRE FABRIC INTO NARROW STRIPS.

SPECIFICATION forming part of Letters Patent No. 674,056, dated May 14, 1901.

Application filed November 3, 1900. Serial No. 35,308. (No model.)

To all whom it may concern:

Be it known that I, CHARLES EDGE, a citizen of the United States, residing at Newark, in the county of Essex and State of New Jersey, have invented certain new and useful Improvements in Tools for Cutting Knitted Wire Fabric into Narrow Strips; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

This invention relates to a novel construction of tool for cutting knitted wire fabric into narrow strips, in which by means of the employment of a cutting-tool the fabric is cut or severed and at the same time the sharp edges or points of the cross-strands of wire are turned over or closed down to form loops, whereby a smooth and finished edge is the result.

The knitted fabric in connection with which my present invention is employed is usually made in widths of three or more feet and then cut, by means of the ordinary shears or circular cutters, into narrow strips for chains, belts, and various other purposes. In this method of cutting the knitted wire fabric into narrow strips each cross-strand of wire projects from the side edges of the strip, thereby leaving a rough edge, which has to be turned over by hand or by a second operation in passing the strip through other suitable machinery.

The object of my present invention is to overcome these objectionable features; and the invention therefore consists in the novel apparatus or cutting-tool hereinafter fully described for cutting wire fabric into narrow strips and during the operation of cutting turning down the projecting ends of the cross wires or strands to form loops and provide a finished edge.

The invention consists, furthermore, in the several novel arrangements and combinations of the various parts of the tool, all of which will be hereinafter more particularly de-

scribed and then finally embodied in the 50 clauses of the claim.

The invention is clearly illustrated in the accompanying drawings, in which—

Figure 1 is a plan view of one form of cutting-tool embodying the principles of my invention. Fig. 2 is an end view, and Fig. 3 is a side view, of the same. Fig. 4 is a longitudinal vertical section of the tool, taken on line 4-4 in Fig. 1. Fig. 5 is a horizontal section taken on line 5-5 in Fig. 3, and Fig. 6 is a like section taken on line 6-6 in said Fig. 3 and looking in the direction of the arrow x. Fig. 7 is a cross-section of the knitted wire fabric, with a vertical sectional representation of the cutters of the tool, said section being taken on line 7-7 in Fig. 2; and Fig. 8 is a plan view of the knitted wire fabric, representing the upper cutting blade or knife of the tool in horizontal section, said view illustrating the cutting operation and the bending or turning down of the cut ends or strands of the cross-wires.

Similar letters of reference are employed in all of the said above-described views to indicate corresponding parts.

Referring to said drawings, A indicates the cutting-tool embodying the principles of my present invention, comprising a suitable base a, provided with an open space a', formed by the supporting portion a² and a forwardly-extending offset a³, substantially as shown in Figs. 3 and 4. In practice said tool A, or rather the base thereof, is arranged in a suitable recess A² in the table or bench A', being securely held in place by a bolt or screw A³, which is passed into an opening or hole A⁴ in the side of the table and then through an opening or hole a⁵ in the base a, and finally screwed into the portion A⁶ of the table, as will be clearly evident from an inspection of Fig. 1. To the front a⁷ of the base a I have secured a suitable guide-plate c, having its upper edge c' slightly curved and made in the manner of a knife-edge. Said plate is secured to the base a by means of a screw, and it also has a curved slot c⁸, in which I have arranged a screw c⁹, secured in the face of the base a, and whereby by slightly unscrew-

ing the two screws c^2 and c^4 the guide-plate c can be suitably adjusted and the knife-edge c' brought closely against the sharp edge of the cutting-blade d . This blade d is slotted, as at d' , and is adjustably secured to a top plate a^6 , adapted to slide on a rib or projection a^7 on said offset a^8 by means of a screw d^2 , the head of which rests against a washer d^3 , which can be firmly forced down over the slot d' to hold said blade d in any desired position. By means of the several screws in the plate c and in the blade d said parts can be properly adjusted to the thickness of the knitted fabric which is to be cut into narrow strips, as will be clearly evident. Upon the face or front of said offset or extension a^8 , secured to a suitable slide f (see Fig. 1) and arranged directly in front of the sharp cutting edge d^4 of the blade d , is a second blade e , which is provided with a sharp edge e' . This edge e' of said second blade is enlarged and is spear-shaped in end elevation, as clearly represented in Fig. 3, and is for the purpose of being fitted down into the space between two consecutive ribs or rises b' of the fabric b . It thereby acts as a gage to properly guide the portion of the fabric b to be cut against the cutting edge d^4 of the blade d . The said blade e is slotted at e^2 and is secured, by means of the screw e^3 , to said slide f , the head of the screw e^3 being adapted to be tightly brought down against a washer e^4 , whereby said blade e can be held in any desired vertically-adjusted position against the front or face of the extension a^8 , as will be understood.

As will be seen from an inspection of Fig. 2 of the drawings, the cutting edge d^4 extends upwardly at an angle to the edge d^5 of the blade d , while the remaining portion d^6 of the lower edge of said blade can also be made in the manner of a knife-edge; but such knife-edge is not an absolute necessity.

As has been hereinabove stated and as will be understood more particularly from an inspection of Fig. 1 of the drawings, the slide f is secured against the side of the extension a^8 and the top plate a^6 on said extension by means of a screw f' , which passes through a slot f^2 in said slide and is secured in the side of said extension a^6 . To screw the said screw e^3 , which secures the gage e in position, into the end of said slide f , the latter is enlarged at f^3 , said enlargement being adapted to fit into a cut-away portion a^8 in the top plate, as shown. By slightly unscrewing the screw f' said slide can be moved forwardly or backwardly to bring the spear-shaped edge of the gage e directly over the space between two of said ribs or rises b' of the wire fabric b , and the gage e is then vertically adjusted by means of the screw e^3 . When the slide f and the gage e have been properly adjusted in the manner just stated, the top plate can be moved forwardly by means of a screw-bolt g , working in a screw-threaded hole in a post a^9 on

the base a , by forcing the end of said screw-bolt against the surface a^{10} of the plate a^6 to move it forwardly, at the same time screwing a screw h in a second perforation in said post a^9 into a screw-threaded opening a^{11} in said top plate. When it is desired to move said top plate in the opposite direction, all that is necessary is to turn the screw g , and then by turning the screw h in the opposite direction the top plate, and with it the parts connected therewith, will be returned to their normal positions. On the rib or projection a^7 is an upwardly-extending post a^{12} , which extends through a slot a^{13} in said top plate and is screw-threaded to receive a tightening-nut a^{14} . Said extension a^8 may also be provided with sockets a^{15} and coiled springs i and i' therein, which exert pressure against the under surface of said top plate a^6 and help to securely hold the same in its adjusted position when the nut a^{14} is screwed down upon the post a^{12} . In this manner, as will be clearly evident, all the parts can be quickly and separately adjusted and when adjusted are secured in their fixed positions ready for the cutting operation.

To cut the fabric into narrow strips and at the same time turn down the projecting ends of the severed cross-strands of wire to produce a finished edge, the fabric is slightly cut with a pair of ordinary shears to form the ends b^2 of the strips, and then the piece is placed upon the table A' in such a manner that the spear-shaped edge of the gage e fits down into the space between two of the consecutive ribs b' of the fabric when the latter is to be cut. The operator then takes one end b^2 of the fabric in each hand and draws the cross-strands of the fabric against the cutting edge d^4 of the blade d , whereby each strand is cut or severed as it is brought into contact with said cutting edge of said blade d . During the cutting operation the fabric is pulled in an upwardly direction by the operator, which brings the extending points of the severed cross-strands of the wires against the sides d^7 of the blade d directly above its lower edge, and in thus being forcibly brought against the said sides the sharp points or ends of the strands are bent or turned inwardly and downwardly to form the closed loops. (Clearly indicated in Fig. 8.)

The method or procedure of the device is very simple in its construction and operation, producing in one operation narrow strips of knitted wire fabric in the form of chains or of proper widths for belts and other analogous uses, with their edges in a finished state, which heretofore had to be accomplished by two distinct operations.

Of course I am aware that changes may be made in the several arrangements and combinations of the various parts of the device as herein described and illustrated in the accompanying drawings without departing from the scope of my present invention. Hence I

do not limit my invention to the exact arrangements and combinations of the parts of the cutting-tool herein set forth, nor do I confine myself to the details of the construction 5 of any of the parts thereof.

Having thus described my invention, what I claim is—

1. A tool for cutting knitted wire fabric into narrow strips, and during its cutting operation, bending or turning down the severed ends of the cross-wires to form a finished edge on the narrow strips, comprising, guide-plates and a cutter, against the cutting edge of which the wire fabric is drawn, said cutter 15 having an upwardly-inclining cutting edge, adapted to cut the cross-strands of the fabric, and straight sides directly behind said cutting edge, operating to bend or turn down the severed strands of the fabric to form loops 20 thereon, when the fabric is drawn against the tool, substantially as and for the purposes set forth.

2. A tool for cutting knitted wire fabric into narrow strips, and during its cutting operation, bending or turning down the severed ends of the cross-wires to form a finished edge 25 on the narrow strips, comprising, a lower guide-plate having a sharp upper edge, and an upper guide-plate having a sharp lower edge, said edges being adapted to extend into the space formed between two ribs in the fabric to be cut, a cutter, against the cutting edge of which the wire fabric is drawn, said cutter having an upwardly-inclining cutting 30 edge, adapted to cut the cross-strands of the fabric, and straight sides directly behind said cutting edge, operating to bend or turn down the severed strands of the fabric to form loops 35 thereon, when the fabric is drawn against the tool, substantially as and for the purpose set forth.

3. A tool for cutting knitted wire fabric into narrow strips, comprising, a suitable base, a guide-plate *c*, having a sharp guiding edge *c'*, 45 a cutter *d*, having an upwardly-inclining cutting edge *d'*, and a gage *e*, having a spear-shaped edge *e'*, substantially as and for the purposes set forth.

4. A tool for cutting knitted wire fabric into 50 narrow strips, comprising, a suitable base, an adjustable guide-plate *c*, having a sharp cutting edge *c'*, an adjustable cutter *d*, having an upwardly-inclining cutting edge *d'*, and an adjustable gage *e*, having a spear-shaped edge *e'*, substantially as and for the purposes set forth.

5. A tool for cutting knitted wire fabric into narrow strips, comprising, a suitable base, having a supporting portion *a*² and an extension *a*³ forming a cutting-space *a'*, a top plate 60 adjustably arranged on said extension, a guide-plate *c* on the front of said base and provided with a sharp guiding edge *c'*, and a cutter *d* secured to said top plate and having an upwardly-inclining cutting edge *d'*, substantially as and for the purposes set forth.

6. A tool for cutting knitted wire fabric into narrow strips, comprising, a suitable base, having a supporting portion *a*² and an extension *a*³ forming a cutting-space *a'*, a top plate 70 adjustably arranged on said extension, an adjustable guide-plate *c* on the front of said base and provided with a sharp cutting edge *c'*, and an adjustable cutter *d* connected with said top plate and having an upwardly-inclining cutting edge *d'*, substantially as and for the purposes set forth.

7. A tool for cutting knitted wire fabric into narrow strips, comprising, a suitable base, having a supporting portion *a*² and an extension *a*³ forming a cutting-space *a'*, a top plate 80 adjustably arranged on said extension, a slide *f* on the side of said top plate, a guide-plate *c* on the front of said base and provided with a sharp guiding edge *c'*, a cutter *d* secured to 85 said top plate, having an upwardly-inclining cutting edge *d'*, and a gage-plate *e* having a spear-shaped edge, said plate being secured to said slide *f*, substantially as and for the purposes set forth.

8. A tool for cutting knitted wire fabric into narrow strips, comprising, a suitable base, having a supporting portion *a*² and an extension *a*³ forming a cutting-space *a'*, a top plate 90 adjustably arranged on said extension, a slide *f* on the side of said top plate, an adjustable guide-plate *c* on the front of said base and provided with a sharp guiding edge *c'*, an adjustable cutter *d* connected with said top plate, having an upwardly-inclining cutting 95 edge *d'*, and a gage-plate *e* having a spear-shaped edge, said plate being adjustably secured to said slide *f*, substantially as and for the purposes set forth.

9. The herein-described cutting-tool A for 105 cutting knitted wire fabric into narrow strips, comprising, a base *a*, having a perforation or hole *a*⁴, and means for securing said base to a table or bench, a supporting portion *a*² and an extension *a*³ forming a cutting-space *a'*; a post 110 *a*⁹, a rib or projection *a*⁷, a top plate *a*⁶ on said rib, and bolts or screws in said post for adjusting said plate *a*⁶ on said rib, a slide *f* on the side of said top plate, a guide-plate *c* on the front of said base, a cutter *d* secured to 115 said top plate, having an upwardly-inclining cutting edge *d'*, and a gage-plate *e* having a spear-shaped edge, said plate being secured to said slide *f*, substantially as and for the purposes set forth.

10. The herein-described cutting-tool A for 120 cutting knitted wire fabric into narrow strips, comprising, a base *a*, having a perforation *a*⁴, and means for securing said base to a table or bench, a supporting portion *a*² and an extension *a*³ forming a cutting-space *a'*, a post 125 *a*⁹, a rib or projection *a*⁷, a top plate *a*⁶ on said rib, and bolts or screws in said post for adjusting said top plate *a*⁶ on said rib, a slide *f* on the side of said top plate, a guide-plate *c* 130 on the front of said base, having a screw *c*², and provided with a slot *c*³, a screw *c*⁴ in said

slot, a cutter d , having a slot d' , and a screw d^2 for adjustably securing said cutter to said top plate, an upwardly-inclining cutter edge d^4 on said cutter, a gage-plate e , having a slot e^2 and a screw e^3 for adjustably securing said plate to said slide f , and said blade e having a spear-shaped edge, all substantially as and for the purposes set forth.

In testimony that I claim the invention set forth above I have hereunto set my hand this 2d day of November, 1900.

CHARLES EDGE.
